(57) **CLAIM**

The ornamental design for an information handling system as shown and described.

DESCRIPTION

FIG. 1 is a front perspective view of the information handling system comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof; and

FIG. 7 is a bottom view thereof;

FIG. 8 is a bottom perspective view thereof

FIG. 9 is an upper perspective view of the information handling system in an open position;

FIG. 10 is a right side view of the information handling system in an open position; and,

FIG. 11 is a detailed view of a vent area of the information handling system as identified in FIG. 8.

The broken lines enclosing a portion of the information handling system in FIGS. 8 and 11 represent the extents of the enlarged detail view and form no part of the claimed design. All remaining broken lines in the drawings illustrate portions of the Information Handling System that form no part of the claimed design.
